UNITED STATES PATENT OFFICE.

ERNEST D. CHASE, OF WINCHESTER, MASSACHUSETTS.

GREETING CARD

Application filed June 3, 1925. Serial No. 34,541.

To all whom it may concern:

Be it known that I, ERNEST D. CHASE, a citizen of the United States, and resident of Winchester, county of Middlesex, State of Massachusetts, have invented an Improvement in Greeting Cards, of which the following description, in connection with the accompanying drawing, is a specification, like characters on the drawing representing like parts.

This invention relates to greeting cards and has for its object to provide a novel greeting card in which the messages are printed on message bearing slips that are inserted through slits formed in the card so that normally the message is concealed but may be exposed by withdrawing the slip from the slit. The message bearing slips are so constructed that they can neither be accidentally withdrawn entirely from the card and thus lost, or pushed so far into the slit that they cannot be readily withdrawn.

In order to give an understanding of the invention I have illustrated in the drawings a selected embodiment thereof which will now be described after which the novel features will be pointed out in the appended claims.

Fig. 1 is a view of a greeting card embodying my invention;

Fig. 2 is a rear side view with a portion broken out;

Fig. 3 is a section on the line 3—3, Fig. 2;

Fig. 4 is a view illustrating the manner in which the strip bearing the greeting is inserted into or withdrawn from the slit;

Fig. 5 is an enlarged fragmentary perspective view of a portion of one of the strips and the adjacent portion of the card;

Fig. 6 is a back side view of one of the greeting bearing strips removed.

The greeting card is indicated generally at 1 and it may have any desirable ornamentation or pictorial representation on its face.

The particular card herein illustrated is one which might be used to send greetings to a person departing on a voyage and the pictorial representation on its face illustrates a wharf with pieces of baggage thereon. It will be understood, of course, that the character of the pictorial representation will vary with greeting cards for different purposes.

The card is provided with one or more

slits 2 through which may be inserted strips 3 having printed thereon some message or greeting. Each strip is formed at one end with a tab or finger piece portion 4 by which the strip may be withdrawn from the slit 2 when it is desired to read the message thereon.

I will preferably print the messages on the back side of each strip although this is not essential. I will also preferably so construct the card that the strips are not visible from the back side thereof but only from the front. This may conveniently be done by making the card in two plies 5 and 6 which are united adhesively or otherwise at their peripheral portion as shown at 7. The space between the plies within the peripheral edge thus forms a pocket in which the strips 3 are received. When the strips are fully inserted only the tab or thumb piece 4 will be exposed on the front of the card. When the tab is pulled outwardly the strip will be withdrawn from the slit 2 and the message thereon can be read.

The tab or finger piece 4 may have any desirable shape which will be suitable for the particular card with which it is used. In the illustrated embodiment of the invention these finger pieces are in the form of baggage tags and the slits 2 are so placed with reference to the pieces of baggage illustrated that when the strips are in place the tabs 4 have the appearance of constituting tags for the pieces of baggage.

A purchaser looking for greeting cards of this type desires, of course, to know the character of the greeting on the strips before making the purchase and in order to do this it is necessary to pull the strips out of their slits sufficiently to enable the message thereon to be read. Such would-be purchasers are frequently rather careless in their handling of greeting cards and are liable to pull the strip clear out of the slit in order to read it and then are not always particular to put it back into the slit again so that the message bearing strips frequently become lost or misplaced and cards which are on sale will be found to be minus one or more of such strips.

One of the objects of my present invention is to provide a novel construction by which this undesirable condition will be avoided and I have, therefore, so made the strips that they cannot be readily removed from

the slits. I have also constructed the tab 4 so that it will form a stop to limit the inserting movement of the strip.

The strips 3 preferably have parallel sides 5 and each slit 2 will be just wide enough to freely receive the strip. The lower end of each strip is formed with a lateral extension 8 which acts as a stop to limit the withdrawing movement of the strip from the slit.

10 In order to permit the strip to be removed or inserted if desired I propose to round the lower corner 9 opposite the extension 8, this corner being formed on the arc of a circle struck from the corner 10 15 as a center.

Fig. 4 shows how the strip may be inserted into the slit 2. This is done by turning the strip down into an angular position and inserting the nose or extension 8 20 through the slit as seen in Fig. 4 and then swinging the strip into its vertical position with the corner 10 fulcruming on one edge of the slit 2. In order to entirely remove the strip from the slit it is necessary to withdraw the strip as far as permitted by 25 the extension 8 so that the corner 10 will be at the corner of the slit and then swing the strip from a vertical position around into the horizontal position as shown in Fig. 30 4 after which the extension 8 may be withdrawn from the slit.

The tab or finger piece portion 4 is preferably made wider than the strip 3 thereby 35 to form shoulders 11 which serve as stops to prevent the inserting movement of the strip.

The strip herein shown is, therefore, provided with means for limiting both its inserting movement and its withdrawing 40 movement and, therefore, the strips will not become accidentally misplaced or lost during their inspection by would-be purchasers.

I claim.

1. A greeting card comprising a card 45 member having a pocket and a slit leading to the pocket and a greeting bearing strip

in the pocket and projecting through the slit, the exposed end of the strip constituting a tab or finger piece by which the strip may be withdrawn, said strip having at its lower 50 end a lateral extension on one side only, the corner of said strip on the other side being rounded, said extension limiting the withdrawing movement of the strip when pulled straight outwardly but permitting said strip 55 to be removed by swinging it into an angular position when it is at the outward limit of its movement.

2. A greeting card comprising a card member having a pocket and a slit leading 60 to the pocket and a greeting-bearing strip in the pocket and projecting through the slit, the exposed end of the strip constituting a tab or finger piece by which the strip may be withdrawn, said strip having at its lower 65 end a lateral extension on one side only, the corner of said strip on the other side being rounded, said extension limiting the withdrawing movement of the strip when pulled straight outwardly but permitting 70 said strip to be removed by swinging it into an angular position when it is at the outward limit of its movement, the tab portion of the strip being wider than the body thereof and forming shoulders which limit the inward movement of the strip.

3. A greeting card comprising a card member having a pocket and a slit leading to the pocket, and a greeting-bearing strip in the pocket and projecting through the 80 slit, the exposed end of the strip constituting a pad or finger piece by which the strip may be withdrawn, and said strip having at its opposite end an extension which prevents the strip from being withdrawn from the 85 slit in a straight line but permits the removal of the strip from the slit when it is turned into an angular position.

In testimony whereof, I have signed my name to this specification.

ERNEST D. CHASE.
